UNITED STATES PATENT OFFICE.

HERMAN LANES, OF BROOKLYN, NEW YORK, AND PAUL F. W. MULLER, OF WEST HOBOKEN, NEW JERSEY.

NON-REFILLABLE CONTAINER.

1,205,458.

Specification of Letters Patent. Patented Nov. 21, 1916.

Application filed October 9, 1915. Serial No. 54,946.

To all whom it may concern:

Be it known that we, HERMAN LANES, a citizen of the United States, and resident of Brooklyn, county of Kings, and State of New York, and PAUL F. W. MULLER, a citizen of the United States, and resident of West Hoboken, county of Hudson, and State of New Jersey, have invented certain new and useful Improvements in Non-Refillable 10 Containers, of which the following is a specification.

This invention relates to containers of the non-refillable variety adaptable for containing and dispensing, one at a time, a plurality of compactly arranged superposed pieces of any product of manufacture, as candy or analogous edible substances, chewing gum, etc. The device may also be used for containing leaves or cakes of soap or any 20 product which it is desirable to inclose and protect for hygenic or sanitary reasons.

The invention has for its object to provide an article of the character named which is inexpensive, simple in construction and 25 readily operable; and it comprises an outer casing, an inner holder for directly carrying the product and a slide for discharging said product, all as will be hereinafter fully described and specifically set forth in the 30 annexed claims.

In the accompanying drawings forming part of this specification, Figure 1, is a plan view in blank of a sheet adapted for forming the outer casing of the device; Fig. 2, 35 a side view of the formed outer casing; Fig. 3, a view of the front end thereof; Fig. 4, a plan view in blank of a sheet adapted to form one member of the inner holder; Fig. 5, a side view showing said member formed; Fig. 6, a plan view in blank of a sheet 40 adapted to form the other member of the holder; Fig. 7, a side view showing said member formed; Fig. 8, is a side view showing the said holder assembled and filled with 45 a plurality of leaves of a product to be dispensed; Fig. 9, is a perspective view of the completed device looking toward the rearward end thereof; and Fig. 10, is a similar view looking toward the front end of the 50 device and showing the slide moved outwardly to deliver one leaf of the contents of the device.

In the accompanying drawings one form of our device is illustrated embodying a rectangular container adapted for holding a

limited number of rectangular leaves, but we do not confine ourselves to the specific shape shown, as it is obvious that other shaped and proportioned containers may be used without departing from the spirit and scope of our invention.

In said drawings 1, indicates a blank sheet of thin metal or other suitable material of a proportion adapted for forming the outer casing A, Fig. 2, of the drawings, and having extensions *a* and *b*; said casing embodies the top wall 2, side walls 3, and the bottom wall 4, all formed integral by bending the sheet 1, on the lines 5, 6, 7 and 8, the adjacent edges of the two parts of the bottom wall 4, being connected by a suitable joint, as 9. Having formed said casing the extensions *b* are bent at right angles to form a flange or stop for contact with the front end of the inner holder, hereinafter described, and the extensions *a*, are left extended on a plane with their connected walls until said holder is introduced. The holder is designated by the letter B, Fig. 8, of the drawing, and it comprises the top member 80 C and the bottom member D. The member C embodies the top plate 10, the depending flange 11, at the forward end thereof, and the cap 12, at the rearward end thereof, all of said parts formed integral from the blank 85 metal sheet E, shown by Fig. 4, of the drawings; and the member D comprises a delivery-slide embodying the bottom plate 13, the thumb-piece 14, the flange 15 and the upright stops 16, adapted for limiting the outward movement of the slide D, to prevent the removal thereof.

The member C, is provided in its top plate 10, with slots 17, which engage and hold a semi-elliptical plate-spring F, adapted for holding the product, as the rectangular leaves G, in secure superposed arrangement on the slide D, whereby they may be readily delivered by the forward movements of said slide. The end wall of the cap 12, is provided with an integrally formed inwardly pressed lug 18, which maintains the leaves G, in position sufficiently pushed forward to allow the flange 15, of the slide D, to engage their inner ends and prevent said slide from pushing said leaves backwardly against the end wall of the cap 12, by frictional action during its rearward movements.

In the operation and use of the invention 110

the product comprising the leaves G is placed on the slide D, and said slide is then connected and manually held in connection with the member C, as shown by Fig. 8, of the drawings, thus completing the inner holder B. Said holder being then fully charged with the product to be dispensed is pushed into the casing A, through the rearward end thereof, and the extensions a, are bent at right angles to their connected walls over the cap 12, as shown in Fig. 9, of the drawings, whereby the holder B, is securely locked within the casing A, and the thumb-piece 14 is in position for operating the slide D. To extract the product it is simply necessary to move the slide forwardly as far as it will go, one leaf of product being carried outwardly with each forward movement of the slide. To facilitate removal of the outwardly moved leaf of product recesses d, are formed in the bottom of the plate D, to accommodate the thumb and finger of the person removing the leaf.

It is especially noteworthy that the several parts of this device are formed integral from single sheets of metal, whereby an exceedingly inexpensive article of manufacture is produced which most effectually encloses and protects the contained product from all contaminating influences while at the same time admitting of its ready removal. Further, a container is provided which cannot be re-filled after its original contents has been removed.

Having thus described our invention, what we claim as new, and desire to secure by Letters Patent, is:—

1. A non-refillable container for carrying and dispensing a plurality of superposed articles, comprising an outer casing composed of one sheet and having integrally formed locking flanges, and an inner holder comprising a fixed member and a slidable member, said flanges locking said holder within said casing, substantially as shown and described.

2. In a non-refillable container, the combination, with a casing open at each end and having integral extensions; of a holder held

within said casing by means of said extensions, said holder comprising a fixed member having a feeding-spring, and a slidable member, said holder adapted to contain and dispense a plurality of superposed articles, one at a time, substantially as shown and described.

3. In a non-refillable container, the combination, with a casing composed of one sheet of material and having integral locking flanges at each end; of a holder locked within said casing by means of said flanges, said holder comprising a fixed member having a feeding spring, a capped rear end and a flanged front end, and a slidable member having a flanged rear end and a flanged front end making a thumb-piece, said holder adapted to contain a plurality of superposed articles, and said slidable member adapted to discharge said articles, one at a time, substantially as shown and described.

4. In a non-refillable container for carrying and delivering a plurality of superposed pieces of manufactured product, one at a time, the combination, with a casing formed of a single sheet and having bent flanges at each end; of a holder comprising a member fixed within said casing by means of said bent flanges, and having an attached feed-spring, a capped end closing one end of said casing, and a flanged end partly closing the other end of said casing, said capped end having an inwardly extended lug, and a slidable feeding-member having an inner flanged end for engaging said pieces, and an outer flanged end making a thumb-piece, and side stops for limiting the outward movements of said slidable member, substantially as shown and described.

In testimony that we claim the foregoing as our invention we have signed our names in the presence of two witnesses, this sixth day of October, 1915.

HERMAN LANES.
PAUL F. W. MULLER.
